CLAIM

I claim the ornamental design for the collapsible colander, as shown and described.

DESCRIPTION

FIG. 1 is a perspective view of a collapsible colander, showing our new design.

FIG. 2 is a front view of the collapsible colander, the back view being identical.

FIG. 3 is a left side view of the collapsible colander, the right side view being identical.

FIG. 4 is a top view of the collapsible colander; and,

FIG. 5 is a bottom view of the collapsible colander.

Features illustrated in broken lines form no part of the claimed invention.

1 Claim, 5 Drawing Sheets
